UNITED STATES PATENT OFFICE.

JAMES H. McCARTNEY, OF FRANKFORT, NEW YORK.

LABEL-CASE.

SPECIFICATION forming part of Letters Patent No. 377,764, dated February 14, 1888.

Application filed April 21, 1887. Serial No. 235,611. (No model.)

To all whom it may concern:

Be it known that I, JAMES H. McCARTNEY, of Frankfort, in the county of Herkimer and State of New York, have invented certain new and useful Improvements in Label-Cases; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improved case for the storage and retention of labels; and it consists in the mechanism herein pointed out, described, and claimed.

My invention relates more particularly to a case for use with that class of labels that are printed in a continuous web or sheet and are separated therefrom as required. It could also be used in any situation where it would be desirable to separate portions of paper from a continuous web or roll.

In the drawings presented, Figure 1 represents a plan view of my case. Fig. 2 represents a front elevation of the same; and Fig. 3 represents a vertical section of my case on line A B, Fig. 1.

Like reference-figures refer to like parts in the several figures presented, and are so referred to in this specification.

Referring more specifically to the drawings in describing the construction and operation of my device, 1, Figs. 1, 2, and 3, represents the walls of a rectangular box or case, as plainly shown in plan in Fig. 1.

2, Figs. 1, 2, and 3, represents a roller that is journaled at each end in slotted bearings formed in the walls of the case in such manner as to admit of its free rotation, as shown at 3, Figs. 1, 2, and 3. These slots extend upward from the journals of the roller to the top of the case, such construction being employed to admit of the free introduction or removal of the roller therefrom. Upon this roller is wound the continuous web of paper or labels, the free end thereof being passed through slot 4, Figs. 2 and 3, in front of case, and extending outwardly therefrom, as shown at 5, Figs. 1, 2, and 3. The bottom portion of the front of the case, as shown at 6, Figs. 2 and 3, is firmly fastened to the walls of the case, and is

really a part thereof. The upper portion, as shown at 7, Figs. 1, 2, and 3, is so constructed as to admit of its free vertical movement in the walls of the case. In the construction shown the movable portion of the front is grooved or recessed, as shown at 8, Fig. 1, to admit of the reception of corresponding projections, 9, Fig. 1, on the walls of the case. The line of separation or cut, forming the division between the fixed and movable portions of the case, forms the slot 4, hereinbefore referred to. The movable portion 7 of the front of the case is held down upon the bottom portion thereof, or upon the superimposed web of labels or paper when the same is in the slot, by means of spring 10, Figs. 1, 2, and 3, or its equivalent. Spring 10 is pivoted at 11, Figs. 1, 2, and 3, to the wall of the case in such manner as to admit of its being swung thereon into position. (Shown in dotted lines 12, Fig. 1.) This frees the movable portion 7 of the case and admits of its removal from the case. At an appropriate point on the front of the case I locate a projecting strip or plate, of metal or other suitable substance, having a serrated edge, as shown at 13, Figs. 1, 2, and 3. The web of labels or paper passes over this, as shown at 14, Figs. 1, 2, and 3. I also provide a spring, as shown at 15, Figs. 1 and 3, one end of which is firmly attached to the case and the other end contacting with the end or periphery of the roller 2, the purpose of which is to prevent the roller revolving at a faster rate than the removal of the paper therefrom would require.

It will be observed that the front of the case extends slightly beyond the sides and top thereof, as shown at 16, Figs. 1, 2, and 3, and is molded or finished on the edges. The purpose of this is found in the fact that I intend to combine a number of these cases in much the same manner that drawers are arranged in a cabinet or case, and the projecting molded edges heretofore referred to furnish a neat and workmanlike finish to the same.

Having described the construction of my device, its mode of operation is as follows: Spring 10 is swung into the position shown in dotted lines in Fig. 1, when the movable portion 7 of the front of the case is removed therefrom. The roller 2, having a web of paper or labels wound thereon, is introduced into the slotted bearings 3 in the walls of the case, bringing spring

15 into contact therewith, and the free end of the web or paper brought outside the case. The movable portion of the front of the case is then replaced and spring 10 swung into position. (Shown in Fig. 1.) The device is then 5 in its operative position.

It will be observed that the movable portion 7 of the front of the case is held upon the web or paper by a greater or less pressure, depending upon the elasticity of spring 10. It is also 10 obvious that I do not use either edge of slot 4 as a tearing or separating edge, its function being to hold the web under tension when the same is torn by proper contact with the serrated edge of plate 13. The use of labels printed 15 in a continuous web and only separated therefrom as required possesses obvious advantages over the usual custom of storing them loosely, as waste is thereby nearly entirely 20 avoided.

It is obvious that various changes in the construction of my device could be made without departure from the central features shown in my invention; hence I do not limit myself 25 to the specific construction herein described and pointed out.

What I claim as new, and desire to secure by Letters Patent, is—

1. In a label-case having a spool wound with

labels, the spool and labels thereon mounted 30 to be rotated in the case, the combination therewith of the stationary and movable sections of the case and the spring for impinging the movable section of the case against the label.

2. In a label-case having a spool wound with 35 labels, the spool being mounted in the case to be rotated, the combination, with the stationary and movable sections of the case, of the spring for maintaining the movable section of the case in contact with the label between the 40 opposing surfaces of the two sections, and the projecting strip of metal having a serrated edge on the front of the case, substantially as set forth.

3. In a label-case, the combination of the 45 stationary and movable front sections thereof, the spring for holding the movable section in contact with the labels between the stationary and movable sections, and the projecting strip of metal having a serrated edge on the front 50 of the case, substantially as set forth.

In witness whereof I have affixed my signature in presence of two witnesses.

JAMES H. McCARTNEY.
